United States Patent Office

Des. 195,848
Patented Aug. 6, 1963

195,848

BAPTISTRY

Martin F. Wiedemann, Jr., Box 776, Muscatine, Iowa

Filed Mar. 5, 1962, Ser. No. 69,093

Term of patent 14 years

(Cl. D29—23)

The FIGURE is a perspective view of a baptistry showing my new design. The undisclosed sides are substantially the same in appearance as the sides shown except as indicated on the drawings.

I claim:

The ornamental design for a baptistry, as shown and described
